UNITED STATES PATENT OFFICE.

ARTHUR E. RIDEOUT, OF CHICAGO, ILLINOIS, ASSIGNOR TO NATIONAL BINDING MACHINE COMPANY, OF NEW YORK, N. Y., A CORPORATION OF NEW YORK.

STRIP-SERVING DEVICE.

1,314,216.

Specification of Letters Patent. Patented Aug. 26, 1919.

Application filed April 28, 1914, Serial No. 834,899. Renewed December 17, 1918. Serial No. 267,213.

To all whom it may concern:

Be it known that I, ARTHUR E. RIDEOUT, a citizen of the United States, and a resident of Chicago, in Cook county, State of Illinois, have invented an Improvement in Strip-Serving Devices, of which the following description, in connection with the accompanying drawings, is a specification, like letters on the drawings representing like parts.

10 The present invention relates to an improvement in strip serving devices, the object being to provide an apparatus in which the strip, to be used subsequently for sealing packages or the like, may be held stationary while it is being moistened or otherwise rendered adhesive.

15 In the drawings which form a part of this specification and in which I have illustrated 20 a single embodiment of my invention,

Figure 1 is a side elevation,

Fig. 2 is a side elevation of the oscillating carriage and stop mechanism in detail with the parts in the relative positions which 25 they occupy when the carriage is in motion toward the tape supply, or in the operation of moistening the tape, parts of the frame work being broken away to show the moistening mechanism.

30 Fig. 3 is a detail view partly in vertical section on the line 3—3 of Fig. 1,

Fig. 4 is a detail view of the tape severing mechanism illustrating the relative positions of the parts when the knife is in normal inoperative position.

35 Fig. 5 is a side elevation of part of the carriage showing the relative positions of the parts when the carriage is moving away from the tape supply.

40 It will be understood that the drawings submitted herewith are for illustrative purposes only, and are intended to represent but one embodiment of a strip serving device made in accordance with my invention.

45 This particular form of machine, according to Fig. 1, comprises a holder 1, for a supply of tape, a fixed platen 2, a carriage member arranged to move alternately toward and away from the tape supply and hereinafter 50 referred to as an oscillating carriage which is adapted to carry means 3 for rendering adhesive, strips of tape either gummed or ungummed, suitable ways 4 for the said carriage, and tape severing means. In the 55 present case, the device illustrated is adapt-

ed to carry a supply of gummed tape, strips of which are drawn out and moistened by means of apparatus more particularly described below. The platen 2, which is shown as located adjacent to the tape holder 1 and above the strip moistening means, is rigidly mounted so that, after a strip of tape 9 has been drawn from the supply, it may be pressed between this unyielding platen and the moistening apparatus to more effectually impregnate the glue on the tape with the moistening fluid.

The oscillating carriage referred to above, and shown in detail in Fig. 2 of the drawings, comprises a frame portion 5 supported upon rotary bearings or wheels 6 which run upon suitably shaped ways or tracks 4. Mounted upon this oscillating carriage, I have provided mechanism adapted to grip the free end of the tape when the carriage reaches that end of its course adjacent to the tape supply. Upon its direction being reverse, a strip is drawn out a sufficient distance to expose the desired length of tape, whereupon the tape end is automatically released and the strip drawn out is in position to be moistened. As shown in Figs. 2 and 3, the tape gripping means comprises in part a fixed transverse bar 7 suitably mounted on the frame work 5 of the oscillating carriage to engage the free end of the tape. Adjacent thereto is another similar but movable bar 8 adapted to be held in spring pressed engagement therewith thus securely gripping the tape between them. In order that this bar 8 may be raised and lowered alternately to grip and release the tape strip, it is mounted upon a pair of slidable supports 10 adapted to slide in bearings 11 positioned at both sides of the carriage and forming a part of the frame work thereof. To hold the transverse bars out of engagement with each other, these supports are provided at their lower ends with latches 12 adapted to engage the end of spring pressed bolts 13 when the carriage reaches the end of its strip drawing oscillation, and to be disengaged therefrom when the carriage returns to its position adjacent to the tape supply. For this purpose the bolts 13, mounted in suitable bearings 14 at each side of the carriage, are provided with projecting lugs 15 adapted to engage corresponding adjustable stops 16 (Fig. 1) to disengage the latch 12. The slidable sup-

ports 10 also have projecting lugs 17 which engage corresponding adjustable cam shaped stops 18 positioned at the opposite end of the machine from that carrying the stops 5 16 and adapted to depress the slideable supports so that the latches 12 may reengage the bolts 13 thus separating the transverse bars 7 and 8. Upon release of the latches 12, the supports are pressed upwardly by means 10 of springs 19, carrying with them the transverse bar 8 which coacts with the fixed transverse bar 7 to grip the strip. The parts are then in proper position to draw out another strip of tape (Fig. 5).

15 In order that the free end of the tape may always be presented between the two transverse bars referred to above, I provide guiding rollers, the roller 20 being journaled in the frame work of the tape support and 20 the roller 21 journaled on a movable arm 22 also mounted on the tape support and adapted to yield against spring pressure when the oscillating carriage bears against it at the end of its moistening oscillation.

25 While the strip is being drawn out, the parts mounted upon the carriage occupy the relative positions shown in Fig. 5 of the drawings. Referring to this figure, the moistening roller 3 is suitably journaled in the 30 frame work of the oscillating carriage to rotate in a supply of water, or in a supply of some adhesive material, in case the machine is to be operated with ungummed tape. When the carriage reaches the end of its 35 oscillation away from the tape supply, marked in the present instance, by a pair of stops 18 and 23 (Fig. 1) the movable tape gripping bar 8 is pressed down to release the tape in the manner heretofore described, 40 and the moistening roller 3 is simultaneously released to engage the tape, these parts now occupying the relative positions shown in Fig. 2 of the drawings. The mechanism controlling the operation of the moistening 45 roller comprises lugs 24, shown in the present case as projecting from extensions 24^a of the shaft of the moistening roller, and latches 25 pivoted at 26 on opposite sides of the frame 5 of the carriage and adapted to 50 be held in spring pressed engagement with the lugs 24 when the parts are in the position shown in Fig. 5. To effect this engagement, the extensions 24^a are positioned to engage adjustable cam shaped stops 27 (Fig. 1) 55 similar to the stops 18 described in connection with the tape gripping mechanism, but positioned to operate at the end of the motion of the carriage toward the tape supply. Upon contact with these cam shaped stops 27, the extensions 24^a are 60 pressed downwardly against pressure of the springs 28, and the latches 25 are forced into engagement with the said lugs 24, as shown in Fig. 5 of the drawings, by pressure of a spring 29, thus holding the moisten- 65 ing roller down and out of contact with the platen. Reversing the operation, in order to disengage the latches 25 from the lugs 24, stops 23 are provided, suitably mounted on ways 30 forming a part of the frame work 70 of the machine so that the stops may be moved back and forth to accommodate different lengths of tape. The latches 25 are also provided with projecting lugs 31 adapted to engage the stops 23 just mentioned and 75 which press the latches out of engagement with the lugs 24, thus releasing the moistener. When disengaged in this manner, the moistener is pressed upwardly against the unyielding platen with sufficient pressure from 80 the spring 28 upon the tape strip during the moistening operation to thoroughly incorporate the gum and water.

When the carriage is in motion toward the tape supply, the strip of tape is not only 85 moistened, but it is also severed by means of a cutting mechanism which co-operates with the carriage. Fig. 1 indicates the arrangement of the cutting mechanism relative to the entire apparatus. Referring now to Fig. 4, 90 which shows the cutting mechanism in detail, the latter comprises a fixed blade 32 suitably mounted adjacent to one end of the platen, a co-operating movable blade 33 pivoted so as to swing across the path of the 95 strip of tape to sever it from the supply, and suitable means for actuating the movable blade. This movable blade is provided with a projecting lug 34 and a spring 35 adapted to hold it normally out of operative 100 position with respect to the fixed blade. Referring again to Fig. 1, where mechanism for actuating the movable blade is shown in connection with the oscillating carriage, a lever 36 is pivoted in the fixed framework 105 of the apparatus so that its free end normally rests in the path of a trip member 37 mounted on the frame of the oscillating carriage and adapted to yield when the carriage moves away from the tape supply and to 110 remain rigid during the return motion. At the opposite end of the lever 36 is pivoted one end of a connecting rod 38, the other end of which is similarly connected to a second lever 39 pivoted to the frame work of the 115 machine in a position adjacent to the tape support. The free end 40 of this last mentioned lever 39 forms a cam shaped portion adapted to engage a toggle 41 shown in detail in Fig. 4. This toggle 41 is adapted to 120 be moved vertically in guides 42 also attached to the fixed frame work of the machine. At the upper end of the toggle, there is a projecting arm 43 adapted to engage the lugs 34 heretofore described as projecting from the movable blade 33. It will be understood that when the carriage moves away from the tape supply, the trip 37, so pivoted on the carriage as to yield in one 125 direction and to remain rigid in the opposite 130

direction, yields sufficiently to pass over the free end of the lever 36, here shown as cam shaped. When the carriage is reversed, however, the trip 37 now rigid, contacts with the 5 free end of the lever, tilting the same forward sharply thus actuating the companion lever 39 through the connecting rod 38 and effecting a movement of the movable blade 33 by a thrust of the toggle and its project- 10 ing arm. In connection with the said toggle 41 I have provided a spring 44 designed to accelerate the return movement of the toggle after it has actuated the movable blade.

It will be understood that the carriage 15 member herein referred to may be caused to oscillate by any suitable means; but I have shown for this purpose mechanism whereby the said carriage member may be moved back and forth by hand power. This mecha- 20 nism comprises a handled lever 45 (Fig. 1) having one end pivoted at 46, and provided with a longitudinal slot 47. A pin 48 projecting from the movable carriage engages the said longitudinal slot so that when the 25 lever arm is moved back and forth, the sides of the slot bear against the pin 48 thus moving the carriage in the direction of motion of the lever. The carriage is further provided with a roller 49 suitably journaled in 30 the frame thereof adjacent to the gripping mechanism heretofore described, its function being to press the tape strip constantly against the platen. This roller has a plurality of projecting peripheral flanges 50 held 35 normally in spring pressed engagement with the platen and the gummed side of the tape by means of springs 51 positioned to press upwardly against the shaft 52 of the said roller, the purpose of the flanges being to 40 afford a minimum of surface so that the gum will not adhere thereto in such quantity as to hinder efficient operation of the device.

In operation, the free end of the tape is brought down under the roller 20 and over 45 the roller 21, extending somewhat beyond the latter. The oscillating carriage is then advanced toward this free end, the parts being in the position shown in Fig. 2. The tape end runs between the fixed bar 7 and the 50 movable bar 8 until continued movement of the carriage brings the lugs 15 on the bolt 13 into contact with the stop 16, whereupon the gripping mechanism is pressed into operation and seizes the tape. Simultaneously 55 therewith, the cam stops 27 engage the lugs 24 of the moistening roller 3 and the latter is pressed down out of contact with the platen, in which position it is held by means of the spring pressed latch 25. By swing- 60 ing the operating lever away from the tape supply, the carriage is caused to move in the same direction, drawing with it the strip of tape 9 (Fig. 5) held securely by the gripping means in the manner heretofore described. 65 The stops 23 and the cam stops 18 are ad-

justable longitudinally of the machine, the latter along ways 53, and serve both to determine the length of strip to be drawn out by stopping the carriage at any predetermined point and also to release the tape 70 gripping mechanism and the tape moistening mechanism. When the latter have operated as heretofore described in detail in connection with the description of their several parts, the carriage is again moved toward 75 the tape supply, this time effecting not only the moistening of the tape but also causing the strip to be severed in the manner likewise previously described in detail. From the foregoing description and method of 80 operation, it will be obvious that a machine of the kind under consideration may be operated with considerable rapidity to serve strips of adhesive tape in definite lengths and in proper condition for being applied 85 to boxes, packages, or other articles to be sealed.

My invention is not limited to the specific form shown in the drawings and described at length in the specification. Obviously 90 there is a wide range of equivalents for most of the elements of this device, which may be substituted for those herein shown and described without departing from the spirit of my invention.

I claim as my invention:—

1. A strip serving device, comprising in combination a holder for a supply of tape, a platen, means for drawing a strip of tape from the supply, and oscillating means adapted to coöperate with the platen and the strip to render the latter adhesive.

2. A strip serving device comprising in combination a holder for a supply of tape, means for drawing a strip of tape from the supply, and means adapted to be moved 105 across the strip to render the same adhesive.

3. A strip serving device comprising in combination a holder for a supply of tape, a rigid platen, means for drawing a strip 110 from the tape supply to a position adjacent to the platen, an oscillating member adapted to traverse the platen and to press the strip of tape against the latter, and means mounted on the oscillating member to render the strip adhesive.

4. A strip serving device comprising in combination a holder for a supply of tape and an oscillating member having means for drawing out a strip of tape and means for 120 rendering the strip adhesive.

5. A strip serving device comprising in combination a holder for a supply of tape and an oscillating member having means for drawing out a strip of tape, when moving 125 away from the supply, and means for rendering adhesive the strip thus drawn when returning toward the supply.

6. A strip serving device comprising in combination a holder for a supply of tape, 130

a fixed platen, an oscillating member having means for drawing a strip of tape from the supply and holding the said strip against the platen, and means adapted to render the strip adhesive while it is held against the platen.

7. A strip serving device comprising in combination a holder for a supply of tape, oscillating means for drawing a predetermined length thereof from the supply, and oscillating means for rendering adhesive the strip thus drawn.

8. A strip serving device comprising in combination a holder for a supply of gummed tape, an oscillating member having means for drawing a strip from the tape supply, a platen, means on the oscillating member for moistening the strip and pressing it against the platen, and severing means operatively connected with the oscillating member.

9. A strip serving device comprising in combination a holder for a supply of gummed tape, a platen, an oscillating member adapted to move toward and away from the tape supply and having tape gripping means and tape moistening means positioned adjacent to the said platen, the said gripping means being adapted to draw a strip from the tape supply as the oscillating member moves away therefrom and the moistening means being adapted to moisten the gummed strip as the oscillating member moves toward the tape supply.

10. A strip serving device comprising, in combination, a holder for a supply of tape, oscillating means movable in one direction to draw out a strip of tape from the supply and adapted to moisten said strip when moving in the opposite direction, and means for severing the moistened strip.

11. A device for serving strips of tape in condition for application to a package or

the like, comprising in combination, a holder for a supply of tape, and means adapted to be advanced along and underlying a strip of the said tape in moistening contact therewith.

12. A device for serving strips of tape in condition for application to a package or the like, comprising in combination, a holder for a supply of tape, means adapted to be advanced along a strip of the said tape in moistening contact therewith, and means for holding the strip in position for engagement with the moistening means.

13. A device for serving strips of tape in condition for application to a package or the like comprising in combination, a holder for a supply of tape, a platen, strip-moistening means movable along the platen and the strip, and strip-pressing means positioned in advance of said moistening means to press the strip of tape against said platen.

14. A device for serving strips of tape in condition for application to a package or the like comprising in combination, a holder for a supply of tape, and an oscillating carriage member having tape engaging means for rendering the tape adhesive.

15. In a device for serving strips of tape in condition for application to a package or the like, the combination of a holder for a supply of tape, means for moistening a strip drawn therefrom, and means adapted to be advanced with said moistening means to support the strip in moistener-engaging position.

In testimony whereof, I have signed my name to this specification, in the presence of two subscribing witnesses.

ARTHUR E. RIDEOUT.
